FOREIGN OBJECT DETECTOR

Don E. Smith, Port Matilda, Pa., assignor to HRB-Singer,
Inc., State College, Pa., a corporation of Delaware

Filed May 2, 1967, Ser. No. 6,919

Term of patent 14 years

(Cl. D52—6)

FIG. 1 is a side elevational view of a foreign object detector, showing my new design, the opposite side being substantially a mirror image thereof;

FIG. 2 is a top plan view thereof;

FIG. 3 is a bottom plan view thereof;

FIG. 4 is a front elevational view of the end of the detector on the right, in FIG. 1; and

FIG. 5 is an elevational view of the opposite end thereof.

The dominant features of my new design are shown in solid lines in the drawing.

I claim:

The ornamental design for a foreign object detector, substantially as shown and described.
